STOCKING

Jacob Dean Isley, Snow Camp, N. C., assignor to Liberty Hosiery Mills, Inc., Liberty, N. C.

Application April 29, 1952, Serial No. 19,517

Term of patent 14 years

(Cl. D47—7)

To all whom it may concern:

Be it known that I, Jacob Dean Isley, a citizen of the United States, residing at Snow Camp, in the county of Alamance, and State of North Carolina, have invented a new, original, and ornamental Design for a Stocking, of which the following is a specification, reference being had to the accompanying drawing, forming part thereof.

In the drawing:

Fig. 1 is a fragmentary rear view of a stocking, showing my new design;

Fig. 2 is a side view of the stocking of Fig. 1; and

Fig. 3 is a bottom view of the stocking of Fig. 1.

I claim:

The ornamental design for a stocking, as shown.

JACOB DEAN ISLEY.
